CHAIR DESK SUPPORTING ARM

Arthur P. Brashear, Jr., Temple, Tex., assignor
to American Desk Manufacturing Company,
Temple, Tex., a corporation of Texas

Application July 8, 1952, Serial No. 297,644

4 Claims. (Cl. 155—125)

1

The present invention relates to combination chair and desk constructions and more particularly relates to an improved desk supporting means in such constructions.

The primary object of the invention is to provide an adjustable desk supporting means that will not wobble, that may be sturdily fixed in any selected adjusted position and that includes a readily accessible fastening means for holding the supporting means in selected adjusted positions.

Another object of the invention, ancillary to the primary object, is to provide a novel chair leg and desk supporting post construction whereby the desk supporting post is held more rigidly in selected adjusted positions than has been heretofore possible.

Yet another object of the invention is to provide a novel gusset plate arrangement for adding additional rigidity to the chair leg which is used in conjunction with the desk supporting means.

A final object of the invention to be mentioned specifically is the provision of a device of the character described which is attractive in design and construction, inexpensive of manufacture and highly efficient in its operation.

These, together with various ancillary objects and features of the invention which will later become apparent as the following description proceeds, are attained by this invention, a preferred embodiment of which has been illustrated by way of example only in the accompanying drawings, wherein:

Figure 1 is a perspective view of a combination desk and chair in which the present invention is incorporated;

Figure 2 is an exploded view of a portion of the combination chair and desk disclosing the novel chair leg and desk supporting means of the present invention;

Figure 3 is an enlarged sectional view showing the interconnection between the chair leg and the desk supporting means;

Figure 4 is a sectional view taken substantially along section line 4—4 of Figure 3; and

Figure 5 is a sectional view taken substantially along section line 5—5 of Figure 1.

Throughout the various views of the drawings and in the following description, like reference numerals are utilized to designate like parts.

Referring now more specifically to the accompanying drawings in detail, the numeral 10 designates the combination chair and desk construction in its entirety. This construction comprises generally a frame including rear legs 12, front legs 14 and 16 and a seat supporting por-

2

tion including scroll members 18 and 20 and a book compartment pan 22. The desk supporting means indicated generally by the numeral 24 is mounted on the chair leg 16 and a desk or top 26 is mounted on the desk supporting means.

Referring now to Figures 2-5, the novel construction and arrangement of the chair leg 16 and the desk supporting means 24 will be clearly observed. Chair leg 16 comprises an angular lower section 28 and an upper tubular section 30. The tubular upper section 30 of the leg 16 is of rectangular configuration, being shown as a square in cross section in the preferred embodiment illustrated. The sections 28 and 30 of the leg 16 are integrally joined to one another at the junction of the upper edges of the scroll member 20 and the book compartment pan 22. Gusset plate 32 is spot welded as at 34 to the scroll member 20 and the pan 22 and is electric welded as at 36 to the rectangular, tubular upper section 30 of the leg 16 in order to tie the tubular upper section 30 rigidly into the frame of the chair.

The desk arm supporting means designated generally by the numeral 24 comprises a post 38, consisting of a rectangular, tubular upper section 40 and an angular lower section 42. The post 38 is adapted to be telescopically received on the leg 16 with the tubular upper section 40 of the post 38 concentrically surrounding the tubular upper section 30 of the leg 16.

To secure the post 38 on the chair leg 16, the front and outer side faces of the leg 16 are provided with apertures 44 and 46 respectively. From an examination of Figures 2 and 3, it will be noted that the apertures 44 on the front face of the leg 16 are disposed adjacent the junction of the rectangular upper section 30 and the angular lower section 28, while the apertures 46 are disposed on the outer side face of the leg 16 on the angular portion 28 of the leg, being spaced somewhat below apertures 44. Post 38 is formed with aperture 48 on the front face of the angular section 42 thereof, which aperture 48 is adapted to align with one of the vertically spaced apertures 44 of the leg 16. Upon the side face of the post 38 in the angular portion 42 thereof and spaced below aperture 48 is a second aperture 49 (Fig. 4) adapted to align with a selected of apertures 46 in the angular portion of leg 16.

Figure 3 of the drawings clearly shows the desk supporting post 38 at its lowermost position on the leg 16 with the rectangular upper section 40 terminating adjacent the scroll member 20 of the chair and the angular section 42 extending

considerably below the scroll member 20 and overlying the angular section 28 of the leg 16. Fasteners 59 and 52 retain the post 38 on the leg 18. By this construction, it can be seen that the present desk arm supporting means comprises both the advantages of telescoping and angular sections. By providing the rectangular tubular section 49 and the corresponding section 30, the post 38 is telescopingly supported in its lowermost position down to the scroll member of the chair frame thereby gaining the rigidity of telescoping sections. Further, the angular section 42 of the post 38 extends downwardly beyond the scroll member 20 of the chair frame and overlies the angular section 28 of the leg 16 to further increase the rigidity of the post 38 by providing this post with the attributes of an elongated angular section which may adhere to the chair leg for a greater portion of its length than would a corresponding tubular section. Therefore, by providing these combined advantages, the supporting means adds greatly increased rigidity in combination chair and desk articles of furniture.

To mount the desk or top 26, the rectangular, tubular section 49 of the desk supporting post 38 has angle brackets 54 and 56 secured to the upper end thereof. Angle bracket 54 has one of its flanges 58 welded or otherwise secured to the outer side face of the tubular section 49 whereas the angle bracket 56 has its side face 60 secured to the front face of the section. Thus, brackets 54 and 56 extend perpendicularly to one another, each having an upper flat face in which apertures 62 are punched whereby the desk top 26 may be secured thereto. It is to be noted that these angle brackets 54 and 56 provide sufficient area to eliminate the need for an arm rest extending from the desk top to one of the rear legs 12 of the chair.

From the foregoing description, the construction and operation of the desk supporting means is believed to be apparent. However, since numerous modifications and changes will occur to those skilled in the art after a perusal of the foregoing specification taken in conjunction with the accompanying drawings, it is not desired to limit the invention to the exact construction shown and described; but, all suitable modifications and changes may be resorted to falling within the scope of the appended claims.

Having described the invention, what is claimed as new is:

1. In a combination desk and chair construction, a frame including a vertically extending chair leg, desk supporting means adjustably secured to said chair leg, said leg comprising an angular lower section and a tubular upper section, said supporting means being vertically adjustable along said tubular upper section, said tubular upper section being rectangular in cross section and having a plurality of vertically spaced apertures therein, said support means comprising a post telescopingly received on said leg, said post having apertures therein aligning with selected apertures in said leg, fastening means extending through said aligned apertures and holding said

leg and post in a selected fixed position with respect to one another, said post comprising a tubular upper section and an angular lower section concentrically surrounding said leg, a pair of braces secured to the upper end of said post, said braces being perpendicularly related to one another and being disposed on a common plane for supporting a desk.

2. In a combination desk and chair construction, a frame including a vertically extending chair leg, desk supporting means adjustably secured to said chair leg, said leg comprising an angular lower section and a tubular upper section, said supporting means being vertically adjustable along said tubular upper section, said frame further including a pair of seat supporting members joining said chair leg at the junction of said upper and lower sections, a gusset plate interconnecting said chair leg and said seat supporting members to additionally rigidify said leg.

3. In a combination desk and chair construction, a frame including a vertically extending chair leg, desk supporting means adjustably secured to said chair leg, said leg comprising an angular lower section and a tubular upper section, said supporting means being vertically adjustable along said tubular upper section, said frame further including a pair of seat supporting members joining said chair leg at the junction of said upper and lower sections, said leg having one set of vertically spaced apertures on the front face thereof at the junction of said upper and lower sections and a second set of vertically spaced apertures below said junction, said supporting means comprising a post telescopingly received on said leg and having vertically spaced apertures aligned with selected apertures of said sets on said leg, said post comprising a tubular upper section and an angular lower section, said post upper section being disposed above said seat supporting members and said post lower section extending below said seat supporting members.

4. In a combination desk and chair construction, a frame including a vertically extending chair leg, desk supporting means adjustably secured to said chair leg, said leg comprising a lower section and a tubular upper section, said supporting means being vertically adjustable along said tubular upper section, said tubular upper section being polygonal in cross-section and having a plurality of vertically spaced apertures therein, said support means comprising a post telescopingly received on said leg, said post having apertures therein aligning with selected apertures in said leg, fastening means extending through said aligned apertures and holding said leg and post in a selected fixed position with respect to one another, said post comprising a tubular upper section and a lower section concentrically surrounding said leg.
